UNITED STATES PATENT OFFICE.

PETER E. MCINTOSH AND RUSSELL O'CONNELL, OF KALAMAZOO, MICHIGAN.

BOILER PLUG.

Application filed September 23, 1921. Serial No. 502,823.

To all whom it may concern:

Be it known that we, PETER E. MCINTOSH and RUSSELL O'CONNELL, citizens of the United States, residing at the city and county of Kalamazoo, State of Michigan, have invented certain new and useful Improvements in Boiler Plugs, of which the following is a specification.

This invention relates to improvements in washout plugs for locomotives, although the invention is adaptable to a great variety of uses.

The object of the invention is to provide such a plug which is very secure and strong and which can be very readily detached and removed.

Objects relating to details and economies of construction and operation will definitely appear from the detailed description to follow.

The objects of the invention are accomplished by the devices and means described in the following specification. The invention is clearly defined and pointed out in the claims.

A structure which is a preferred embodiment of the invention is fully illustrated in the accompanying drawing, forming a part of this application, in which:

Fig. I is an elevation view of a locomotive washout plug embodying the features of the invention, a portion of the boiler plate being shown in section.

Fig. II is an end elevation view of the structure appearing in Fig. I taken from the lefthand end.

Fig. III is a similar elevation view from the righthand end of Fig. I, the set screw being shown broken off.

Fig. IV is a detail vertical sectional view taken on line 4—4' of Figs. II and III.

Fig. V is a detail perspective view of the bushing.

In the drawing the sectional views are taken looking in the direction of the little arrows at the ends of the section lines, and similar numerals of reference refer to similar parts throughout the several views.

Considering the numbered parts of the drawing by their numbers, 1 is a section of the boiler plate. 2 is the threaded bushing inserted into the plate, the outer end 3 of which bushing is square, forming a bearing for the flange of the plug. The inner end 55 of the bushing is divided into two oblique spiral surfaces 4, 4, there being longitudinal

notches 5, 5 separating these two oblique surfaces.

The plug 6 is provided with an outwardly projecting flange 7 at its outer end having a bearing seat against the outer end 4 of the bushing between which a washer 3' may be interposed. The inner end of the plug 6 is provided with a cross-arm or oppositely projecting lugs 8, 8 of such dimensions as to pass readily through the longitudinal slots 5, 5, so that they may be turned into engagement with the spiral surfaces 4, 4 at the inner end of the bushing, thus producing a joint similar to a bayonet joint, except that the oblique ends enable the tightening of the flange of the plug against the bushing. A square projecting end 9 is provided on the end of the plug to enable the same to be turned into position by the use of a wrench.

A laterally projecting plate 11 carries the overhanging curved segment 10 which overhangs the end of the bushing. A set screw 12 fits into one or another of the screw holes 13 through the segment portion to engage the periphery of the projecting end of the bushing to lock the plug against rotation. A lock nut 14 is provided for the set screw 12 which retains the same securely in place.

It will thus be seen that the plug can be brought against its bearing surface by very strong pressure by the use of the wrench and that when the same is thus urged into position it may be very readily secured in that position by the set screw, which set screw may be retained effectively by the lock nut. The plug can be very readily removed by hand by simply releasing the lock nut and the set screw, a matter of very great advantage in the speedy handling of such structures, there being a large number of them on each locomotive.

A series of screw holes are provided for the locking set screw so that it will be possible to shift the position of the set screw in the event of wear. The set screw might make a seat for itself that would make it difficult to secure a fine adjustment because of the tendency of the plug to slip back to permit the set screw to drop into an old seat.

These plugs are for use on locomotives required to resist very high steam pressure and they must be adjusted very tightly and securely.

Having thus described our invention, what we claim as new, and desire to secure by Letters Patent, is:

1. In a structure of the class described, the combination of a screw bushing with a bearing seat at its outer end and an inner end divided into opposed symmetrical spiral surfaces with longitudinal slots leading thereto, a plug with a flanged bearing to fit the bearing at the outer end of the bushing and with longitudinally projecting opposed lugs adapted to pass through the longitudinal slots and engage the said spiral surfaces, a square projection on the plug for turning the same, a transversely projecting plate carrying a curved segment with a series of screw holes, a set screw for insertion through the said segment to lock the plug in closed position, and a lock nut for the set screw, as specified.
2. In a structure of the class described, the combination of a bushing with a bearing seat at its end and an inner end divided into opposed symmetrical spiral surfaces with longitudinal slots leading thereto, a plug with a flanged bearing to fit the bearing at the outer end of the bushing and with longitudinally projecting opposed lugs adapted to pass through the longitudinal slots and engage the said spiral surfaces, a square projection on the plug for turning the same, a transversely projecting part, and a set screw for insertion through the said part for locking the plug in closed position, as specified.
3. In a structure of the class described, the combination of a bushing with a bearing seat at its outer end and an inner end divided into opposed symmetrical spiral surfaces with longitudinal slots leading thereto, a plug with a flanged bearing to fit the bearing at the outer end of the bushing and with longitudinally projecting opposed lugs adapted to pass through the longitudinal slots and engage the said spiral surfaces, a transversely projecting part, and a set screw for insertion through the said part for locking the plug in closed position, as specified.
4. In a structure of the class described, the combination of a bushing with a bearing seat at its outer end and inner end divided into opposed symmetrical spiral surfaces on its inner face with longitudinal slots leading thereto, a plug with a flanged bearing to fit the bearing at the outer end of the bushing and with longitudinally projecting opposed lugs adapted to pass through the longitudinal slots and engage the said spiral surfaces, and a set screw means to lock said plug against rotation to secure it in place.
5. In a structure of the class described, the combination of a bushing with a bearing seat at its outer end and an inner end divided into opposed symmetrical spiral surfaces on its inner face with longitudinal slots leading thereto, a plug with a flanged bearing to fit the bearing at the outer end of the bushing and with longitudinally projecting opposed lugs adapted to pass through the longitudinal slots and engage the said spiral surfaces, and an external manually manipulated means for securing said plug against rotation.
6. In a boiler plug, the combination with a one piece externally threaded bushing having its outer end faced to provide a bearing seat and its inner end conformed to provide oppositely disposed symmetrical spiral surfaces, said bushing having opposed internal longitudinal grooves extending from end to end thereof and leading to said spiral surfaces, and a one piece plug having a peripheral flange at its outer end, faced on its inner side to coact with said bearing seat of said bushing, said plug having opposed lugs adapted to be introduced through the said longitudinal grooves of said bushing into engagement with the said spiral surfaces thereof whereby the bearing faces of said bushing and plug are clamped together by a rotative movement of the plug, said plug being adapted to receive a wrench.

In witness whereof, we have hereunto set our hands and seals in the presence of two witnesses.

PETER E. McINTOSH. [L. S.]
RUSSELL O'CONNELL. [L. S.]
